Primary Examiner — Cathron C Brooks*Assistant Examiner* — Christian P. McLean(74) *Attorney, Agent, or Firm* — Greenberg Traurig, LLP(57) **CLAIM**

The ornamental design for a container assembly, as shown and described.

DESCRIPTION

FIG. 1 is a front perspective view of our container assembly;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The oblique lines depicted on the window of the container assembly indicate that the window is transparent. The oblique lines depicted on the sleeve retaining the tag suspended from the handle of the container assembly indicate that the sleeve is transparent.
